UNITED STATES PATENT OFFICE.

JOHN RACOSKY, OF JEROME, PENNSYLVANIA.

CUT-OUT SWITCH FOR MINE-TROLLEYS.

1,343,475.

Specification of Letters Patent. Patented June 15, 1920.

Application filed April 28, 1917, Serial No. 165,169. Renewed March 13, 1920. Serial No. 365,626.

To all whom it may concern:

Be it known that I, JOHN RACOSKY, a citizen of the United States, residing at Jerome, in the county of Somerset and State of Pennsylvania, have invented certain new and useful Improvements in Cut-Out Switches for Mine-Trolleys, of which the following is a specification, reference being had to the accompanying drawings.

- 10 This invention relates to an improved cut-out switch for mine trolleys, whereby the possibility of the electrocution of the miners by accidental contact with the trolley wire will be entirely obviated.
- 15 It is another object of my invention to provide a very simply constructed switch for the above purpose, automatically actuated by the trolley wheel, whereby the circuit is closed from the source of current 20 through a section of the trolley wire, and such circuit automatically broken after the trolley wheel passes out of contact with the wire section.

And it is a further object of the invention 25 to provide an automatically actuated cut-out switch for mine trolleys which consists of relatively few parts of simple form so that the device can be produced at relatively small cost and readily installed in the mine 30 corridor.

With the above and other objects in view, my invention consists in the novel features of construction, combination and arrangement of parts to be hereinafter more fully 35 described, claimed and illustrated in the accompanying drawings, in which,

Figure 1 is a side elevation of a portion of a trolley line such as is used in mines, in which my improved switch has been installed, one of the switch units being shown in section;

Fig. 2 is a similar view after the switch has been actuated and the supply circuit closed through the section of trolley wire;

Fig. 3 is a section taken on the line 3—3 of Fig. 1;

Fig. 4 is a section taken on the line 4—4 of Fig. 1;

Fig. 5 is a detail perspective view of one 50 of the contact blocks;

Fig. 6 is a similar view of one of the oscillatable circuit closing members and the actuating rod connected thereto;

Fig. 7 is a detail vertical section showing

the latch means for the movable switch element.

My improved switch, in its preferred embodiment, consists of two units which are disposed in predetermined spaced relation. Each of these units includes a base block 5 of suitable insulating material, which is suspended by means of the bolt indicated at 6, from one of the hangers 7 in which the insulated current conductor 8 is supported closely adjacent to the roof of the line corridor. The under side of the block 5 has each of its ends provided with a central, longitudinal groove or channel, and the metal contact members 9 and 10 respectively, are each provided with a relatively narrow web 11 and 12 extending into the respective channels of the base block 5. These webs are rigidly fixed within the channels by means of a plurality of transverse screws or bolts indicated at 13. A contact member 9 is provided with a longitudinal extension 14 on its inner end, having a beveled face indicated at 15, the purpose of which will presently appear. The opposed end of the other contact member 10 also has a beveled or inclined face 16. In the section of the trolley line illustrated in the drawings, the contact members 9 of the spaced switch units are connected to each other by the section of trolley wire shown at 17, the ends of said members which project beyond the ends of the blocks 5 having openings bored therein to receive the terminal portions of the wire and being provided with clamping screws 18 for binding engagement with the wire. The other contact members 10 are likewise connected in a similar manner to the corresponding members of other switch units by the trolley wire sections. The ends of the conductor 8 are bared and secured to the contact members 10 by means of the binding screws 19.

To the inner end of each of the members 10, a triangular-shaped circuit closing element 20 is oscillatably connected, as indicated at 21, and when the circuit between the switch units is open, the inclined face 22 of said element is engaged with the inclined face 16 of the member 10, while the inclined face 23 of said element is spaced from the inclined face 15 of the contact member 9. To the inclined face 22 of the element 20 of one switch unit and adjacent

the end thereof, the lower end of a vertically movable rod or bar 24 is pivotally connected, said rod being freely movable in the opening or passage 25 extending vertically 5 through the contact member 10. A similar vertically movable rod 26 is pivotally connected to the inclined face 23 of the element 20 of the other switch unit, said latter rod being vertically movable in an opening or 10 chamber 27 provided in the base block 5. To the upper end of each of the rods 24 and 26, one arm of a bell crank lever 28 and 29 respectively, is connected, said levers being fulcrumed upon suitable rods or pins 30 15 fixed in the blocks 5. The other upwardly projecting arms of the bell crank levers are connected to each other by the rod 31 which consists of a plurality of sections and is movable through bores formed in the blocks 20 5. The rod sections are connected to each other within the base block by the sleeves 32 of insulating material, and a clamping device indicated at 33 also connects adjacent sections of the rod 31 to lengthen or 25 shorten the same when it is desired to space the switch units farther apart or dispose the same nearer each other.

Each of the rods 24 and 26 is provided with a flattened portion having spaced openings 34 therein. A spring-pressed latch pin 35 is adapted for engagement in said openings to prevent the casual longitudinal movement of the rod, said pins, however, yielding under a positive pressure exerted on the 30 rod. This holding pin for the rod 24 is suitably mounted in the contact member 10 of the switch unit, while the holding pin for the rod 26 is mounted in the base block 5 of the other switch unit.

40 From the above description, the operation of the invention will be understood as follows. Assuming that the mine car is moving in the direction indicated by the arrow, the trolley wheel W riding upon the bottom 45 face of the contact member 9 strikes the base surface of the oscillatable circuit closing element 20 and moves the same from the position seen in Fig. 1 to the position seen in Fig. 2, the inclined face 23 of said element being engaged with the inclined face 15 of the contact member 9. In this oscillation of the element 20, the rod 26 is forced upwardly, thereby oscillating the bell crank lever 29, and through the medium of the rod 50 31 imparting a similar oscillation to the lever 28 of the other switch unit. The rod 24 will thus be forced downwardly, oscillating the block 20 of the latter switch unit and engaging its inclined face 23 with the 55 inclined face 15 of the contact member 9 of the latter switch unit, as clearly shown in Fig. 2. Thus, the circuit will be closed from the current supply wire 8, through the contact block 10, element 20 and the contact 60 block 9 of one switch unit, through the 65

stretch of trolley wire 17, the member 9, element 23 and member 10 of the other switch unit, back to the conductor 8, so that the motor of the car will receive current while the wheel W is in contact with this particular stretch of trolley wire. When the wheel, however, strikes the other switch element 20, it will oscillate the same to disengage its inclined face 23 from the inclined face 15 of the contact member 9 and return said element to the position seen in Fig. 1, thus reversing the movement of the rod 31 and forcing the rod 26 of the other switch unit downwardly, thereby also disengaging the face 23 of the element 20 in this unit from the face 15 of the contact member 9, thereby breaking the circuit through the trolley wire section. The element 20 of the next adjacent switch unit in advance will be in a position corresponding to the position of the element 20 shown at the left in Fig. 2 of the drawings so that the circuit will be closed through the next adjacent section of trolley wire 17, the members 10 and the conductors 8. Thus, throughout the length of the trolley wire, 80 the several sections 17 will be supplied with the current only while the trolley wheel is engaged thereon or with the contact members to which the wire section is connected, and immediately after the trolley wheel 90 passes beyond the switch unit to an adjacent trolley wire section, the section in the rear becomes dead or, in other words, the circuit to said trolley wire section from the conductor 8 is broken. The spring of the latch 100 pin 35 in each switch unit is sufficiently strong to retain the circuit closing element in the position to which it has been moved so that the circuit between the switch units will not be accidentally closed by the casual 105 pivotal movement of said elements.

From the above, it will be seen that I have produced a very simple and effective automatic cut-out switch for mine trolleys which will eliminate danger to the miners and obviate the possibility of their electrocution or serious injury by a clean contact with the charged trolley wire. The device consists of relatively few parts which are all of simple form, and it will, therefore, be appreciated that the invention can be produced and installed in the mine corridor at relatively small cost. The form of the several contact members and the manner of securing the same to the base block may, of course, be 110 greatly varied, and the construction and arrangement of the several other elements employed is likewise susceptible of considerable modification. It will be understood that my improved switch will operate in the 115 manner above set forth when the car is traveling in either direction upon the track. It is also to be understood that I reserve the privilege of adopting all such legitimate changes as may be fairly embodied within 120 125 130

the spirit and scope of the invention as claimed.

Having thus fully described my invention, what I desire to claim and secure by

5 Letters Patent is:

1. An automatic cut-out switch for trolleys including spaced units each consisting of spaced contact members insulated from each other, a trolley wire section connecting 10 the adjacent contact members of the switch units, a current conductor connected to the other contact members of the switch units, a movable circuit closing element normally engaged with the latter contact member of 15 each unit, and operating connections between said elements whereby when one of the elements is engaged and moved by the trolley wheel into circuit closing relation with the first named contact of the switch 20 unit, the circuit closing element of the other switch unit is moved to a like position and the circuit closed through the trolley wire section.

2. An automatic cut-out switch for trolleys including spaced units each consisting of spaced contact members insulated from each other, a trolley wire section connecting the adjacent contact members of the switch units, a current conductor connected 25 to the other contact members of the switch units, an oscillatable circuit closing element mounted upon the latter contact member of each switch unit, and operating connections between said elements, whereby when one of 30 the elements is engaged and moved by the trolley wheel into circuit closing relation with the first named contact of the switch unit, the circuit closing element of the other switch unit is moved to a like position and 35 the circuit closed through the trolley wire section.

3. An automatic cut-out switch for trolleys including spaced units each consisting of spaced contact members insulated from 40 each other, a trolley wire section connecting the adjacent contact members of the switch units, a current conductor connected to the other contact members of the switch units, a movable circuit closing element normally 45 engaged with the latter contact member of each unit, operating connections between said elements whereby when one of the elements is engaged and moved by the trolley wheel into circuit closing relation with the 50 first named contact of the switch unit, the

circuit closing element of the other switch unit is moved to a like position and the circuit closed through the trolley wire section.

4. An automatic cut-out switch for trolleys including spaced units each consisting of spaced contact members insulated from each other, a trolley wire section connecting the adjacent contact members of the switch units, a current conductor connected to the other contact members of the switch units, a movable circuit closing element normally engaged with the latter contact member of each unit, a bell crank lever for each switch element, means operatively connecting the 60 circuit closing element to one arm of the bell crank lever, and means connecting the other arms of the bell crank levers to each other whereby, when one of the circuit closing elements is engaged by the trolley wheel and 65 moved into circuit closing relation to the first named contact of one switch unit, the circuit closing element of the other switch unit is moved to a like position.

5. An automatic cut-out switch for trolleys including spaced units each consisting of spaced contact members insulated from each other, a trolley wire section connecting the adjacent contact members of the switch units, a current conductor connected to the 80 other contact members of the switch units, a movable circuit closing element normally engaged with the latter contact member of each unit, a bell crank lever for each switch element, means operatively connecting the 85 circuit closing element to one arm of the bell crank lever, means connecting the other arms of the bell crank levers to each other whereby, when one of the circuit closing elements is engaged by the trolley wheel and 90 moved into circuit closing relation to the first named contact of one switch unit, the circuit closing element of the other switch unit is moved to a like position, and latch 95 means for engagement with the connections between said elements and the bell crank levers to hold the circuit closing elements in either position against casual movement.

In testimony whereof I hereunto affix my signature in the presence of two witnesses. 100

JOHN RACOSKY.
